CLAIM

The ornamental design for a wheel for a motor vehicle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a wheel for motor vehicle; FIG. 2 is a front view thereof; and,

FIG. 3 is a top view thereof.

In the drawings the broken lines depict portions of the wheel that form no part of the claimed design.

1 Claim, 3 Drawing Sheets
